SUPPORTING RACK

Ferdinand V. Smolderen, Mount Vernon, N. Y., and John P. Cody, Bernardsville, N. J., assignors to Refined Syrups & Sugars, Inc., Yonkers, N. Y., a corporation of New York

Application June 5, 1945, Serial No. 597,640

9 Claims. (Cl. 248—136)

1

This invention relates to foldable stands or racks provided with a cradle or frame to receive a container, the frame or cradle being tiltable for the purpose of pouring from the container. In such racks or stands it is desirable that provision be made for readily removing the container for replacement or refilling, and that provision be made for the convenient support of a receptacle into which the contents of the container may be poured.

An object of the invention is to provide an improved foldable rack having a mounting for tiltably supporting a container and having a shelf for supporting a receptacle into which the contents of the container may be poured.

Another object of the invention is to provide a rack permitting the tilting of a container supported thereby without danger of accidental displacement or falling of the container from the rack during the operation of pouring therefrom.

A further object of the invention is to provide a support or rack for tiltably supporting a container, with means for intercepting any drip or spillage.

Further objects and advantages of the invention will be apparent from the drawings and detailed description.

Fig. 1 of the drawings is a view in side elevation of a rack embodying the invention. The view shows a container in the rack.

Fig. 2 is a front elevation of the organization shown in Fig. 1.

Fig. 3 is a plan view of the organization shown in Fig. 1, certain parts being eliminated or broken away.

Fig. 4 is a perspective view of the tiltable cradle shown in Figs. 1, 2 and 3.

Fig. 5 is a side view of the rack in folded condition, without the cradle and container.

Fig. 6 is a fragmentary side elevation, showing a modification in which the trunnion on the cradle is retained in its mounting by a fastening device.

Fig. 7 is a fragmentary rear view of the modification shown in Fig. 6.

Fig. 8 is a fragmentary vertical section showing a modification in which the shelf for supporting a receptacle is in the form of a tray.

Fig. 9 is a view in elevation of a modified form of container pouring spout.

Fig. 10 is a top plan view of the spout shown in Fig. 9.

Fig. 11 is a detail in side elevation and on an enlarged scale, showing the toggle-like joint between the two sections of a folding cross brace

2

which forms a part of the rack shown in Figs. 1, 2, 3, 5, 6 and 7.

The rack shown is composed of a pair of A-form frames or supports, designated as a whole by 1. These are rigidly secured in spaced relation to each other by iron horizontal straps or flat crosbars 2, 3 and 4. Rigidity is secured by the bent-over ends of bars 2 and 3 and by firm riveted connection of bars 2 and 3 to the rear legs 5, 5 and of bar 4 to front legs 6, 6 of the A-form supports.

The legs 5 and 6 of the rack are preferably made of angle iron incorporated into the rack in the manner shown. The ends of bars 2 and 3 are bent to extend perpendicularly to the body of the bars and are riveted to the rearwardly extending flanges of legs 5, 5. This construction affords a rigid angular attachment of bars 2 and 3 to legs 5, 5 because any pivoting about a connecting rivet, so long as the rivet is reasonably tight, will not result in any change in the angle of the bar in the line of its connection to the other A-form frame. However, any such pivoting will be prevented if the flat inner faces of bars 2 and 3 closely contact the rear edges of legs 5, 5.

The legs 5, 5 and 6, 6 of the A-frames have their forwardly and rearwardly extending flanges at the apex of the frame cut away as at 7 and 8, so that extending flat portions 9 and 10 of the sidewise extending flanges may be bent to the configuration shown. The projections 9 and 10 form a fork or crotch 12 to receive the trunnions of a swinging cradle or tiltable container-frame 26, to be hereinafter described. Beneath the crotch 12 a strap hinge is riveted to legs 5—6, thereby providing a hinged connection 11 between the two legs.

The hinging at 11 of the fore and aft legs 5 and 6 of each of the A-frames, permits the rack to be folded when not in use. When the A-frames are extended for use, the fore and aft legs are braced by folding braces, each of extensible toggle construction. These braces consist of links 14, 15 (see Figs. 1, 5 and 11) which, when extended into alignment with each other, form a rigid brace.

Fig. 1 shows the foldable brace extended and Fig. 5 shows it folded. The links 14 and 15 are pivoted together at 16. By reference to Fig. 11 it will be seen that link 14 extends beyond pivot 16 and is provided with conformations which afford, in cooperation with the conformations of link 15, an effective stop for the opening movement of the toggle, and for retaining the toggle

in extended position. The links 14 and 15 consist of flat iron bars sufficiently thin to permit indentation on one side that produces a projection or elevation of the surface of the opposite side. Link 14 has a projection 17 adjacent the upper edge produced by forging a depression opposite thereto; and link 15 has a recess 18 for reception of projection 17, with a resulting elevation 19 on the side opposite recess 18. In this way a stop is provided for arresting the links 14 and 15 in their extended or alined position. It will be seen that this stop structure is attained from the metal of links 14 and 15 without weakening them. In the same way a projection 20, having a convex spherical surface is provided on link 14 for coaction with a concave spherical depression in link 15. This spherical depression is on the side opposite to spherical protuberance 21. It will be seen that the protuberance 20, together with the recess into which it snaps, forms a suitable latch for holding the links 14 and 15 in extended position. The latching hold may be broken by the application of moderate upward force to links 14 and 15, and thus the rack is readily foldable.

In pouring liquid or other material from a rack-supported tilttable container it is desirable that provision be made for conveniently positioning the receptacle into which the material is to be poured. For this purpose there is provided a shelf 22, hinged at 24 to the rear legs 5, 5 of the two A-frames. A forward portion of shelf 22 rests on crossbar 4. The shelf may be hinged to rear legs 5, 5 in any suitable manner, but as shown the shelf is provided with a pair of projecting studs or pivot pins 24, 24 which extend through holes in the rearwardly extending flanges of legs 5, 5. Shelf 22, as shown, is rectangular and is made of sheet metal or other suitable material in sheet form, having peripheral marginal flanges for rigidity and strength.

In Figs. 1, 2 and 3 the shelf 22 is illustrated as placed in the rack with the flanges depending, so that a free upper surface is provided on which a receptacle may be conveniently placed and removed by sliding motion without interference from any marginal obstruction. There are conditions of use, however, in which it is desirable for the shelf 22 to act as a catch-pan to intercept liquid drippings or material scattered in pouring from the container. For use as a catch-pan the shelf 22 may be mounted in the rack with the flanges extending upwardly, in which position it will become a rimmed tray. Fig. 8 shows this alternative arrangement, wherein the shelf 22 is mounted as a tray or catch-pan.

Mention has been made of the crotches 12, 12 formed by the projections 9 and 10 of each of the A-frames, these crotches receiving the trunnions of a cradle or container-frame designated as a whole by 26. The container-frame or swingable cradle 26 includes a stirrup formed of a flat strip or bar of iron or other suitable material. This strip or bar has two right angle bends to form side strips 27 and 28 and a bottom strip 29. The stirrup is adapted to embrace the container 50; and to the bottom 29 of the stirrup there is attached by rivets a crosspiece 30 on which the container rests. Crosspiece 30 is provided at its ends with upstanding V-flanges 31, 31 which prevent the bottom of the container 50 from shifting forwardly or backwardly in the cradle. A crossbar 32 is hinged at 33 to the top of side strip 27 and is engageable with the upper end of stirrup side 28 between prongs 34, 34.

Each edge of bar 32 is notched as at 35, and the notches interlock with prongs 34, 34. This holds the upper end of stirrup side 28 against any tendency to shift its position with respect to the upper end of stirrup side 27. Crossbar 32 is releasably secured in engagement with side 28 by a latch 36 of spring metal. This latch is riveted at 36a, 36a to stirrup side 28; and the free end of the latch is formed as a thumb piece 36b, by means of which the latch may be conveniently retracted from engagement with the end of crossbar 32. To prevent the top of container 50 from shifting forwardly or backwardly in the cradle, the crossbar 32 is provided with transverse holding pieces 37, 37 having depending lips which engage the container fore and aft.

The parts just described form a cradle or container frame 26 for holding the container 50 in the foldable rack so that the container may be tilted to pour out its contents. To that end the stirrup side bars 27 and 28 have secured thereon trunnions 38, 38; and crossbar 32 is made with a portion 39 upwardly displaced to form a handhold. The cradle 26 is mounted in the rack by placing it therein with trunnions 38, 38 resting in the crotches 12, 12, as is best seen in Figs. 1, 2 and 3.

In Figs. 6 and 7 there is shown an optional additional feature, for securing the trunnions in their crotches against accidental displacement. Each of the A-frame legs 5, 5 may be provided with a shouldered stationary pin 41 held in place by a nut 44. Swingably mounted on each such pin 41 is a resilient hook member 40, engageable by snap action with one of the cradle trunnions, as is shown in Figs. 6 and 7. When retainer hooks 40 are used, the cradle trunnions 38, 38 are of course made long enough to receive the hooks, as is indicated in Fig. 7.

The cradle 26 has dimensions adapting it to the particular container to be suspended therein, and the container may be of any suitable commercial type. The container 50 shown is a familiar type of rectangular metal can, the top of which is customarily provided with an upstanding pouring thimble, normally closed with a screw cap. For dispensing we prefer to replace the screw cap with a funnel-shaped pouring spout such as 42. This spout is threaded at the bottom to screw onto the container thimble, to which it is sealed by a conventional gasket ring (not shown). When dispensing is not in progress the pouring spout may be closed by a suitable cork, wooden stopper or the like 43. Preferably the stopper is held captive to the rack by a chain, as shown.

The spout 42 being funnel-shaped, it pours correctly regardless of the rotative position it assumes when screwed home onto the container thimble. In Figs. 9 and 10 there is shown a modified pouring spout 42' which is so corrugated as to facilitate the pouring of narrow or small streams. The corrugations 43' being close together, one of them can readily be brought to correct pouring position when the spout is screwed home on the container thimble.

Either spout 42 or spout 42' may also be used as a funnel for refilling the container. For most usages, however, the container 50 will be removed from the cradle 26 when the container is empty and be replaced by a full container. In making such replacement, the pouring spout, 42 or 42', will be transferred to the full container.

In compliance with the patent statutes we have disclosed the best form in which we have con-

templated applying our invention. It will be realized, however, that the disclosure is illustrative and not limiting.

What is claimed is:

1. A tiltable container rack, comprising: a pair of foldable A-frames, each including front and back legs, hingedly connected together at the top, extensions from the legs forming a crotch above the hinged connection, folding means beneath the hinged connection for bracing the legs in open position, and a spring latch engageable with a trunnion positioned in the crotch; crossbars connecting the front legs and connecting the back legs of the two A-frames and rigidly securing the A-frames together in spaced relation; a tray pivotally attached to the back legs of the A-frames, said tray resting on a crossbar attached to the front legs of the two A-frames; and a tiltable container frame having trunnions positioned in said crotches, said trunnions being detachably engaged by said spring latches and thereby secured in said crotches.

2. A tiltable container rack, comprising: a pair of foldable A-frames, each including front and back legs, hingedly connected together at the top, extensions from the legs forming a crotch above the hinged connection, and folding means beneath the hinged connection for bracing the legs in open position, crossbars connecting the front legs and connecting the back legs of the two A-frames and rigidly securing the A-frames together in spaced relation; a tray pivotally attached to the back legs of the A-frames, said tray resting on a crossbar attached to the front legs of the two A-frames; and a tiltable container frame having trunnions positioned in said crotches.

3. A tiltable container rack, comprising: a pair of foldable A-frames, each including front and back legs hingedly connected together at the top, extensions from the legs forming a crotch above the hinged connection, retainer means cooperable with a trunnion positioned in the crotch, and a pair of toggle links hingedly connected to the front and back legs and operable in extended position to brace the legs in open position; crossbars connecting the front legs and connecting the back legs of the two A-frames and rigidly securing the A-frames together in spaced relation; a shelf pivotally attached to the back legs of the A-frames, said shelf resting on a crossbar attached to the front legs of the two A-frames; and a tiltable container-holding cradle having trunnions positioned in said crotches, said trunnions being removably retained by said retainer means.

4. A tiltable container rack, comprising: a pair of foldable A-frames, each including front and back legs hingedly connected together at the top, extensions from the legs forming a crotch above the hinged connection, and a pair of toggle links hingedly connected to the front and back legs and operable in extended position to brace the legs in open position; crossbars connecting the front legs and connecting the back legs of the two A-frames and rigidly securing the A-frames together in spaced relation; a shelf pivotally attached to the back legs of the A-frames, said shelf resting on a crossbar attached to the front legs of the two A-frames; and a tiltable container-holding cradle having trunnions positioned in said crotches.

5. A tiltable container rack, comprising: a pair of foldable A-frames secured in spaced relation and having crotches at their apexes; a container-receiving cradle having trunnions positioned in

said crotches, said cradle having crossed supporting members to lie beneath the bottom of the container, having a hinged bar to overlie the container, and having a latch for securing said bar in closed position; a crossbar connecting two corresponding legs of the two A-frames, and a folding shelf pivotally attached to the other corresponding legs of the two A-frames, said shelf resting on said crossbar and being positioned to support a receptacle for receiving material poured from a container mounted in said tiltable cradle.

15 6. A tiltable container rack, comprising: a pair of foldable A-frames secured in spaced relation and having crotches at their apexes; a container-receiving cradle having trunnions positioned in said crotches, said cradle having supporting means to lie beneath the bottom of the container, and having a bar to overlie the container, said bar having a portion bent to form a handle for tilting the container; a crossbar connecting two corresponding legs of the two A-frames, and a folding shelf pivotally attached to the other corresponding legs of the two A-frames, said shelf resting on said crossbar and being positioned to support a receptacle for receiving material poured from a container mounted in said tiltable cradle.

20 7. A cradle for tiltably supporting a container, comprising: a stirrup having means for positioning the bottom of a container therein and having side bars for extending upwardly along the container; a top crossbar hingedly connected to the upper end of one of said side bars and cooperating with the upper end of the opposite side bar to retain a container in said stirrup, said top crossbar having elements extending laterally and downwardly for engaging the upper portion of a container and restraining movement thereof; a spring latch for holding said top crossbar in closed position, said top crossbar having a portion bent to form a handhold for manipulating said cradle; and trunnions on said side bars substantially above the middle thereof, whereby said cradle may be swingably suspended.

25 8. A tiltable-container rack, comprising: a pair of foldable A-frames, each formed of angle irons hinged together at one end and braceable in divergence from each other by toggle bars in alinement with each other, each of said angle irons having a portion cut away to leave a flat part at its hinged end parallel with the axis of the hinge, the adjacent flat parts diverging from each other to form a crotch, said pair of A-frames being rigidly secured to each other in laterally spaced relation; a foldable shelf hinged to the rear angle irons of said A-frames and resting horizontally on a member attached to the front of said A-frames; and a tiltable container-frame having trunnions resting in said crotches.

30 9. A tiltable container rack, comprising: a pair of foldable A-frames secured in spaced relation and having crotches at their apexes; a container-receiving cradle having trunnions positioned in said crotches and having portions for engaging a container and a shelf pivotally attached to two corresponding legs of the A-frames and adapted to be supported by the other two corresponding legs in a substantially level position to support a receptacle for receiving material poured from a container mounted in said tiltable cradle.

FERDINAND V. SMOLDEREN.
